BADGE

Maurice L. Bates, Winchester, Ky.

Application March 19, 1954, Serial No. 29,610

Term of patent 14 years

(Cl. D29—2)

To all whom it may concern:

Be it known that I, Maurice L. Bates, have invented a new, original, and ornamental Design for a Badge, of which the following is a specification, reference being had to the accompanying drawing, forming a part hereof.

The dominant features of my design are shown in full lines.

I claim:

The ornamental design for a badge, as shown and described.
